MECHANICAL REVERSING DEVICE

Application filed April 10, 1928. Serial No. 268,997.

This invention, which is termed a mechanical reversing device, is a mechanical organization adapted to impart alternate opposite rotation to a driven shaft from a drive shaft which is constantly rotated in a single direction. This organization is particularly adaptable for use in connection with washing machines, etc., in which it is necessary to rotate a machine alternately in opposite directions over brief periods of time. In ordinary practice, machines of this kind are generally reversed in their operation by reversing the rotation of the drive shaft, and in case an ordinary steam or gas engine is used, there is obviously a great loss of power and time and, consequently, a decrease in efficiency incurred in the stopping and reversing of the engine or gear connected therewith. In case electric motors are used, the motor is obviously subject to a constant varying load, as the reversing of the motor, as is well known to those familiar with this art, is a source of great power consumption and consequent increase in expense in proportion to the amount of work which is accurately performed.

It is a fundamental object of my invention to develop an organization of simple form and construction which, by means of oppositely rotated clutch members, may be adapted to automatically impart opposite rotation over brief periods of time to a driven shaft from a drive shaft which is constantly rotated in a single direction.

It is a further object of my invention to develop such an organization which is simple and economical in its construction, positive in its operation, and comprises a minimum of wearing parts.

Other objects and advantages of my invention will be better understood from the following specification and claims.

Referring to the drawings, which illustrate a preferred embodiment of my invention, chosen for illustrative purposes only,

Fig. 1 is a plan view, with a cover member removed.

Fig. 2 is an elevational section along the line 2—2 of Fig. 1.

Fig. 3 is an elevational section along the line 3—3 of Fig. 1.

Fig. 4 is a sectional view along the line 4—4 of Fig. 3, and

Fig. 5 is a sectional view taken substantially along the line 5—5 of Fig. 2.

More particularly describing my invention as herein illustrated, numeral 11 indicates a driving organization, such as a motor, having a drive shaft 12 and a driving pinion 13. The mechanical reversing organization generally indicated at 14 is enclosed within a housing 15, comprising a cover member 16 and a bottom member 17, supported in any suitable manner, such as the legs, indicated at 18.

The housing 15 is provided with oppositely disposed bearings 19—19', adapted to receive what I may term a driven shaft 20. A gear, which I may for the purpose of explanation term a driving gear 21, is rotatably mounted upon the driven shaft 20, and is adapted to be driven by the pinion 13, mounted on the drive shaft 12.

In order that the driving gear 21 may have an uninterrupted rotation about the driven shaft 20, friction eliminating means such as the roller bearing organization 22 may be interposed between the driving gear 21 and the driven shaft 20 in a manner such as is illustrated in Fig. 3.

Oppositely disposed on either side of the driving gear 21 and mounted upon the driven shaft 20, I provide what I may term clutch organizations, generally indicated at 30—30'.

These organizations, which are similar in their construction, comprise clutch engaging members 31—31' in the form of collars or sleeves and having clutch engaging faces 32—32' formed therein.

Mounted in the clutch engaging members and enclosed within the collars, are provided what I may term clutch members 33—33'. These clutch members are rigidly mounted upon the driven shaft 20 by means such as the keys 34—34', and may comprise any standard clutch construction, being provided with inner engaging faces 35—35', adapted to engage the clutch engaging faces 32—32' of the clutch engaging members.

For the purpose of describing this organization, the clutch engaging member 31 is 100

termed a forward rotating member and is rigidly connected to the driving gear 21 by means such as screws 36, which engage a flange or other suitably formed projection 37 formed upon the gear 21.

5 The clutch engaging member 31' is termed a rearward rotating member, and is provided with means for receiving a reverse rotation from the gear 21. The construction of this 10 reverse rotating organization comprises a sleeve 40, which is integrally formed with or rigidly attached to the clutch engaging member 31', and extends inwardly toward the driving gear 21, terminating in an inner gear 41.

15 This sleeve 40 is rotatable within an outer collar 43, which is externally provided with gear teeth 44 and with flattened faces 45—45', which are received by the upwardly 20 extending prongs 46—46' of a yoke member 47.

25 The yoke member 47 is rigidly attached to the bottom housing member 17 by means such as the bolts 48. It will be understood that this collar 43, having the outer gear periphery 44, is held stationary by means of the yoke 47, and for the purpose of later explanation, it will be termed a stationary gear.

30 A plurality of dual gears 50 are rotatably mounted upon the face of the driving gear 21, which is adjacent to the rearward rotating clutch member 30'. These dual gears are retained upon the gear face by means such as the bearing studs 51, and are provided 35 with what I may term an inner gear periphery 52 and an outer gear periphery 53, these mentioned gears being adapted to engage the inner clutch driving gear 41 and the outer stationary gear 43 respectively.

40 It will be understood from this construction that during the rotation of the driving gear 21, the dual gears 50 are carried about the drive shaft 20 and through the engagement of the outer teeth 53 with the stationary 45 gear 43, the inner teeth 52 will impart a constant rotation to the clutch engaging member 31' through the inner gear 41.

50 It will be further understood that, by suitably proportioning the size of these gears, the rotation of the clutch engaging member 31' may be of the same annular velocity as the forward rotation of the driving gear 21.

55 From the foregoing description, it will be seen that the driving gear 21 is constantly rotated in what I may term a forward driving direction and the clutch organizations 30—30' are respectively rotated in a forward and rearward driving direction, and it will be obvious that through the alternate engagement of the clutch members 33 and 33' with the clutch engaging members 31 and 31', the shaft 20 may be alternately rotated in opposite directions.

60 For the purpose of bringing the clutch members 33 and 33' and the clutch engaging

members 31 and 31' into alternate firm engagement with one another and maintaining this engagement until such time as the engaged member is automatically released, I provide upon the shaft 20 oppositely disposed 70 slidable collars 60—60', which are provided with annular channels 61—61', the purpose of which will be hereinafter described. The collars 60—60' are adapted to be laterally moved upon the shaft 20 in a 75 direction toward the clutch members 30—30' by means such as coil springs 62—62', these springs being outwardly retained in what I may term fixed collars 63—63', mounted upon the shaft 20 in any suitable manner, 80 such as by means of pins 64—64'.

85 The slidable collars 60—60' are rendered effective to cause an engagement between the clutch members and the clutch engaging members by means of a plurality of levers 70—70', which are pivotally mounted upon an outer face of the clutch engaging members, and are provided with pins 71—71', which are adapted to engage the clutch members 33—33' upon an inward movement of 90 the levers and to effect thereby a firm engagement between the clutch members and the clutch engaging members, as indicated by the position of the rearward driving clutch organization 30' in Fig. 3.

95 It will be understood that the springs 62 and 62' are effective to impart a lateral movement to the collars 60 and 60' in one direction only, and it is necessary to provide means for moving these collars in an opposite, or in 100 the form of the invention illustrated, a clutch disengaging direction.

105 For this purpose I provide yoke members 80 and 80' which are received by the channels 61 and 61' upon the slidable collars 60 and 60', and are adapted to be moved laterally by means of cranks 81 and 81', said cranks being rigidly mounted upon rotatable 110 shafts 82 and 82', the shafts being supported in any suitable manner, such as by the bearings 83.

115 Levers 84 and 84' are outwardly mounted upon the ends of the shafts 82 and 82' and are adapted to receive a partial rotation from 120 slidable rods 85 and 85', carried in suitable bearing members 86 and 86', and inwardly adapted to engage a cam 87, the cam engaging end of the slidable rods being optionally provided with rollers 88. The cam 87 is mounted upon a shaft 87', which is inwardly 125 provided with a gear 89 adapted to be driven by a worm 90 mounted upon a worm shaft 91. The worm shaft 91 is outwardly provided with a pinion 92, which is driven through a train of gears indicated by the gear 93 by means of a driving gear 94, which is shown as being provided upon the extending flange 37 formed on the driving gear 21.

130 It will be understood from the above description and the illustration in Fig. 5 that

the cam 87 is rotated by the driving gear 21, and by imparting a partial rotation to the rotatable shafts 82 and 82', is adapted to effect an alternate lateral movement to the collars 60 and 60' and a consequent disengagement in the oppositely disposed clutch organizations 30 and 30'. This cam is preferably so formed, as indicated by the dotted lines in Fig. 5, as to provide a slight hesitant or neutral position between the alternate disengagement of the clutch members, thus obviating the possibility of undue wear in the clutch members or the stripping of gears due to the possible simultaneous engagement of both clutch members.

My invention is obviously simple in its construction, has a minimum of wearing parts, is positive in its operation, and meets a need in industry for an organization which will effect an automatic reversal in driven shaft rotation from a uni-directionally rotated drive shaft, and it will be understood that, while I have herein described and illustrated one specific embodiment of my invention, various modifications of the same may be readily adapted by those familiar with the art without in the least departing from the spirit and scope of my invention as described above and in the following claims.

I claim as my invention:

1. A mechanical reversing device comprising: a drive shaft; a driven shaft; a drive pinion on said drive shaft; a drive gear rotatable relative to said driven shaft and engaging said pinion; clutch members mounted on said driven shaft; means operable by the rotation of said drive gear for rotating said clutch members in opposite directions; and automatic means rendering said clutch members alternately operable to impart rotation from said drive gear to said driven shaft, said automatic means comprising rotatable shafts, cam means operable by said drive gear and adapted to impart a partial rotation to said shafts, and means mounted between said cam rotated shafts and said clutch members adapted to move said clutch members laterally upon said driven shaft.

2. A mechanical reversing device comprising: a drive shaft; a driven shaft; a drive pinion on said drive shaft; a drive gear rotatable relative to said driven shaft and engaging said pinion; clutch members mounted on said driven shaft; means operable by the rotation of said drive gear for rotating said clutch members in opposite directions; and automatic means rendering said clutch members alternately operable to impart rotation from said drive gear to said driven shaft, said automatic means comprising rotatable shafts, cam means operable by said drive gear and adapted to impart a partial rotation to said shafts, and crank members rigidly mounted upon said cam rotated shafts in engagement with said clutch members and

adapted to impart lateral movement to said clutch members during the rotation of said shafts.

3. A mechanical reversing device comprising: a drive shaft; a driven shaft; a drive pinion on said drive shaft; a drive gear rotatable relative to said driven shaft and engaging said pinion; clutch members mounted on said driven shaft; means operable by the rotation of said drive gear for rotating said clutch members in opposite directions; and automatic means rendering said clutch members alternately operable to impart rotation from said drive gear to said driven shaft, said automatic means comprising rotatable shafts, cam means operable by said drive gear and adapted to impart a partial rotation to said shafts, crank members rigidly mounted upon said cam rotated shafts in engagement with said clutch members and adapted to impart lateral movement to said clutch members in one direction, and resilient means for imparting lateral movement to said clutch members in an opposite direction.

4. A mechanical reversing device comprising: a drive shaft; a driven shaft; a drive pinion on said drive shaft; a drive gear rotatable relative to said driven shaft and engaging said pinion; clutch members mounted on said driven shaft; means operable by the rotation of said drive gear for rotating said clutch members in opposite directions; and automatic means rendering said clutch members alternately operable to impart rotation from said drive gear to said driven shaft, said automatic means comprising cam means operable by said drive gear for imparting lateral movement to said clutch members in one direction, and coil springs engaging said clutch members and adapted to impart lateral movement thereto in a direction opposite to the movement of said cam means.

5. A mechanical reversing device comprising: a drive shaft; a driven shaft; a drive pinion on said drive shaft; a drive gear rotatable relative to said driven shaft and engaging said pinion; clutch members mounted on said driven shaft; means operable by the rotation of said drive gear for rotating said clutch members in opposite directions; and automatic means rendering said clutch members alternately operable to impart rotation from said drive gear to said driven shaft, said automatic means comprising rotatable shaft members, levers rigidly mounted on said shaft members, slideable members in engagement with said levers, a cam rotatable by the rotation of said drive gear adapted to impart sliding movement to said slideable members, and cranks rigidly mounted on said rods in engagement with said clutch members for imparting linear movement thereto.

6. An organization for imparting alter-

nate opposite rotation to a driven shaft comprising: a driving gear concentric with and rotatable about said driven shaft; means for imparting uni-directional rotation to said driving gear; a forward driving clutch engaging member rotatably mounted on said shaft in rigid engagement with said driving gear; a rearward driving clutch engaging member rotatably mounted on said shaft; gears interposed between said driving gear and said rearward driving clutch engaging member for imparting a reverse rotation to said clutch engaging member; clutch members rigidly mounted on said driven shaft and adapted to be engaged by said clutch engaging members; and automatic means for bringing said clutch members into alternate engagement with said clutch engaging members, said automatic means comprising cam means operable by the rotation of said driving gear to impart lateral movement to said clutch members in one direction and resilient means for imparting lateral movement to said clutch members in an opposite direction.

In testimony whereof, I have hereunto set my hand at Los Angeles, California, this 28 day of March, 1928.

FRANK A. GILB.
